UNITED STATES PATENT OFFICE

2,659,905

SUNBATH TENT

Michael J. Rochford, Chicago, Ill.

Application July 25, 1951, Serial No. 238,469

5 Claims. (Cl. 5—362)

1

My invention relates to enclosures for protection of sunbathers, and more particularly to shield them from the annoyance of flies and other insects, and one object is to provide a tent which affords both a restful base on which the bather may lie and a netted cover over the base as a complete protection against flying insects.

A further object is to design the novel tent with sections designed to afford an easy entrance into the tent by the occupant and facilities for the joining of the sections after they have been assembled.

Another object is to provide means inside the tent for maintaining the same in the proper position over the occupant to permit freedom of movement of the body and limbs.

An additional object is to provide means for folding the tent into compact form for transportation by the occupant from place to place.

An important object is to construct the novel tent with a minimum of parts designed to render its production economical and its handling easy for the average person.

With the above objects in view, and any others which may suggest themselves from the description to follow, a better understanding of the invention may be had by reference to the accompanying drawings, in which—

Fig. 1 is a top plan view of the tent, showing the position of the occupant therein;

Fig. 2 is a front elevation;

Fig. 3 is a section on the line 3—3 of Fig. 2;

Fig. 4 is a top plan view of the tent base showing certain parts over the same;

Figs. 5 and 6 are group enlargements of portions in the central region of Fig. 2;

Fig. 7 is a magnified view of a fastening unit occurring in Fig. 5;

Fig. 8 is a similar view of fastening parts as seen in Fig. 6;

Fig. 9 is a front elevation of the tent as gathered up into folded position; and

Fig. 10 is a perspective view of a carrier for handling the folded tent.

In accordance with the foregoing, specific reference to the drawings indicates the base of the tent as an elongated pad 15 which is preferably made of sponge rubber having smooth external surfaces. The bottom surface of the pad is lined with a sheet 16 of waterproof cloth which is cemented or vulcanized to the pad 15 and serves as an external protector for the same.

The cover of the tent is shown as formed of sections 20 and 21, the material thereof being a fabric of fairly close mesh. Such mesh in full

2

size would appear approximately like in Figs. 7 and 8. However, for purposes of clarity, the mesh has been shown much larger in Figs. 1, 2, 5 and 6. The bottom edges of the cover sections 20 and 21 are reinforced by cord sections 17 and 18 formed like half-loops; and the edge of the base pad is grooved longitudinally to seat the cord sections.

Means are provided inside the tent cover at the center and near the ends to keep the same at a suitable height to accommodate the occupant. The element employed in the center to keep the tent cover up is a simple arch 25 of band metal, the ends of the arch having inward bends 26 resting on the base pad 15. The latter has secured to it by cement or other suitable means cross-strips 27 into which the arch bends are inserted as shown in Fig. 3 to maintain the arch in position. The cover supporting elements near the ends of the tent are in the form of arches 30 which also have inward terminal bends 31. However, these are journaled in keeper plates 32 cemented or otherwise secured to the base pad 15 in order to enable the arches 30 to be folded from the upright positions shown in Fig. 1 to the inwardly collapsed positions shown in Fig. 4.

The inner ends of the cover sections 20 and 21 are designed to be mounted in overlapped relation over the arch 25. Thus, the foot section 21 is originally mounted on the arch and carries a fabric tape 35 for reinforcing purposes, such tape being tautly stretched over the arch. The head section 20 of the cover also carries a reinforcing tape 36 which is designed to overlap the tape 35 to a partial extent when the cover sections are to be assembled. In such event, hooks 37 carried by the tape 36 are designed to engage eyes 38 carried by the tape 35 at a number of places along the course of the arch to join the sections of the cover firmly. Since the tape 36 is flexible, the occupant of the tent will have no difficulty manipulating the hooks, which are shown extended in Fig. 7 to hook into the eyes 38. Preferably, the hooks and eyes are carried by discs 40 of cloth stitched to the material of the cover; and the bases of the hooks are preferably ring-shaped and suitably stitched as indicated at 41 in Fig. 7 to the related discs 40. In addition, the cord section 17 carries bottom hooks 45 designed to engage similarly located eyes 46 of the cord section 18 to insure the closing of the cover sections at the bottom.

The end arches 30 are designed to be maintained in upright position by cords 50 which extend from the arches toward the center of the cover to terminate with hooks 51, these engaging

in holes 52 made in the center arch 25. The cords 50 are drawn taut by springs 55 which extend outwardly from the arches 30 to terminate with hooks 56 which engage in keepers 57 carried by the base pad 15. The cords 50 carry metallic finger-hold rings 58 for facility in engaging the hooks 51.

Additional means are provided to lend comfort to the occupant of the tent. Thus, 60 represents a pad designed to support the neck as shown in Fig. 2, such pad carrying the head portions of snap fasteners 61. The pad carries the base portions 62 of the snap fasteners in a longitudinal series, so that the pad 60 may be adjusted forwardly or rearwardly according to the height of the occupant. A similar but narrower pad 65 is provided for supporting the ankles and carries the head portions 66 of snap fasteners, these cooperating with any pair of base portions 67, as in the previous instance, to adjust the position of the pad in relation to those of the occupant's ankles.

It is obvious that one occupying the novel tent as described above will secure the comfort of a cot or bed and exposure to the sun without annoyance from flies, mosquitoes or other flying insects. When the use of the tent is no longer required, it may be unhooked at the center by the occupant to release the head section 20 of the cover and permit the occupant to slide such section back and leave the tent. In order to collapse the same, the cords 50 are first unhooked from the center arch 25; and the springs 55 are then unhooked from the keepers 57 to permit the arches 30 to be folded inwardly upon the base pad 15. The ends of the latter may now be picked up and gathered to assume semi-circular form and join at the top as shown in Fig. 9. The ends of the pad carry securing means 70 which now occur close to each other; and a device is provided for engaging these securing means to keep the tent in the gathered or collapsed position.

The device just mentioned is shown more clearly in Fig. 10 and is a scissor-shaped handle 71. The lower portions of the handle are in the form of hooks 72 which engage the securing means 70 to keep the same gathered. The handle 71 is formed with long slots 73 in its upper portions, for the passage of the hand carrying the handle 71; and a link 74 connects the upper portions of the handle after it has been applied as stated in order to lock them into position. The tent thus assumes the appearance indicated in Fig. 9 and may be carried about from place to place with facility.

It is apparent that the novel tent is an article which provides both comfort for the occupant when lying on a beach or lawn and complete protection against contact or approach by flying insects. The tent has firm elements on the inside which keep its cover in the raised position during use; yet, the cover is sectional in order to facilitate the easy entrance and exit of the occupant and handling of the fastening elements from the inside. Further, means are provided for head and foot comfort inside the tent; and its base is flexible and favorable to assuming the position of a hand grip or valise when gathered up into folded position, so that the tent becomes an article of a compact form; and further means are provided for keeping the tent folded and facilitating its transportation by hand from place to place. Finally, the materials entering into the construction of the tent are of a simple and easily

available nature, making it possible to manufacture the same at reasonable cost.

While I have described the invention along specific lines, various minor changes or refinements may be made therein without departing from its principle, and I reserve the right to employ all such changes and refinements as may come within the scope and spirit of the appended claims.

I claim:

1. A sunbath tent comprising a base pad elongated to accommodate a person in the lying position, a cover of netted fabric surmounting the base pad and secured at the bottom to the edge of the same, and means to maintain the cover in a position sufficiently raised to freely accommodate the person, said means comprising a cross-arch in the center of the tent, a pair of cross-arches near the ends thereof, the latter cross-arches being pivotally mounted upon said base pad to swing from upright positions downwardly upon the base pad, cords extending from the latter arches and terminating with hooks engageable with the center arch, and springs extending outwardly from said latter arches and terminating with hooks engageable with the end portions of said pad to draw said cords into taut condition.

2. A sunbath tent comprising a base pad elongated to accommodate a person in the lying position, a cover of netted fabric surmounting the base pad and secured at the bottom to the edge of the same, and means to maintain the cover in a position sufficiently raised to freely accommodate the person, said means comprising a cross-arch in the center of the tent, a pair of cross-arches near the ends thereof, the latter cross-arches being pivotally mounted upon said base pad to swing from upright positions downwardly upon the base pad, said base pad being of a flexible cushion material adapted to be rolled up at the ends with the central and folded cross-arches on the inside until said ends meet, and means to secure the meeting ends of the pad from separation.

3. A sunbath tent comprising a base pad elongated to accommodate a person in the lying position, a cover of netted fabric surmounting the base pad and secured at the bottom to the edge of the same, and means to maintain the cover in a position sufficiently raised to freely accommodate the person, said means comprising a cross-arch in the center of the tent, a pair of cross-arches near the ends thereof, the latter cross-arches being pivotally mounted upon said base pad to swing from upright positions downwardly upon the base pad, said base pad being of a flexible cushion material adapted to be rolled up at the ends with the central and folded cross-arches on the inside until said ends meet, and means to secure the meeting ends of the pad from separation, said means being extended to form a handle.

4. A sunbath tent comprising a base pad elongated to accommodate a person in the lying position, a cover of netted fabric surmounting the base pad and secured at the bottom to the edge of the same, and means to maintain the cover in a position sufficiently raised to freely accommodate the person, said means comprising a cross-arch in the center of the tent, a pair of cross-arches near the ends thereof, the latter cross-arches being pivotally mounted upon said base pad to swing from upright positions downwardly upon the base pad, said base pad being of a flexible cushion material adapted to be rolled

up at the ends with the central and folded cross-arches on the inside until said ends meet, securing means carried by the ends of the pad and occurring in opposed relation at the meeting points of said ends, and a handle applicable over said securing means and having hooks to engage the same and lock them against separation.

5. A sunbath tent comprising a base pad elongated to accommodate a person in the lying position, a cover of netted fabric surmounting the base pad and secured at the bottom to the edge of the same, and means to maintain the cover in a position sufficiently raised to freely accommodate the person, said means comprising a cross-arch in the center of the tent, a pair of cross-arches near the ends thereof, the latter cross-arches being pivotally mounted upon said base pad to swing from upright positions downwardly upon the base pad, said base pad being of a flexible cushion material adapted to be rolled up at the ends with the central and folded cross-arches on the inside until said ends meet, securing means carried by the ends of the pad and

occurring in opposed relation at the meeting points of said ends, a handle applicable over said securing means and having hooks to engage the same and lock them against separation, said handle being scissor-shaped with the hooks at its inner end, and a link applicable to the outer end of the handle to keep the same in fixed position when said hooks are in engagement with said receptacles.

MICHAEL J. ROCHFORD.
